UNITED STATES PATENT OFFICE.

CHARLES LEE FRISBY, OF COUNCIL BLUFFS, IOWA.

SEED-CORN SEPARATOR.

No. 820,775.

Specification of Letters Patent.

Patented May 15, 1906.

Application filed May 9, 1905. Serial No. 259,598.

To all whom it may concern:

Be it known that I, CHARLES LEE FRISBY, a citizen of the United States, and a resident of Council Bluffs, in the county of Pottawattamie and State of Iowa, have invented certain new and useful Improvements in Seed-Corn Separators, of which the following is a clear, full, and exact description, such as will enable those skilled in the art to which they appertain to make and use the same, reference being had to the accompanying drawings, forming a part of this specification.

My invention relates to certain new and useful improvements in seed-corn separators, and aims to provide a device of this type in which inclined and parallel spaced rolls are employed, the space between the adjacent rolls forming passage-ways for the kernels of grain, such space between each pair of adjacent rolls increasing in regular successive variations from the point at which the grain is fed, thus constituting passage-ways of varying sizes, which permit the varying sizes of kernels to fall therethrough in successive order of increase during their gravitating action.

In the accompanying drawings, in which like characters of reference denote similar parts throughout the several views, Figure 1 is a top plan view of the machine. Fig. 2 is a section through the feed-hopper on line 2 2 of Fig. 1 looking in the direction of the arrow. Fig. 3 is a central longitudinal section, and Fig. 4 is a detail plan view of one of the adjustable journal-blocks in which the roll ends are journaled.

The machine is disposed upon a supporting structure embodying vertical standards 1, suitably connected at their lower portions by virtue of bars 2. The machine-body is formed of side sections 3, which incline downwardly and which are rigidly secured to the upper portions of the vertical standards 2, the latter terminating at the upper edge of the side sections. Side sections 3 are connected at their upper and lower extremities by end sections 4 and 5.

To the upper and lower ends of the respective end sections 4 and 5 spaced parallel cleats 4^a and 5^a are secured, adjustable journal-blocks 4^b and 5^b being mounted between said cleats and constituting bearings for the reduced ends 6 of the inclined rolls. As

shown in the drawings, four of these rolls are employed, (designated 7, 8, 9, and 10,) it being permissible to employ a less or greater number, according to the amount of grain being separated and the speed at which separation is desired. The alternately-arranged rolls—in this instance 8 and 10—are reduced in diameter at corresponding successive intervals throughout their length, as at 8^a and 8^b and 10^a and 10^b, the adjacent rolls 7 and 9 possessing the same diameter throughout their entire length, as shown. By this arrangement of alternately-disposed reduced rolls the distance between each pair of adjacent rolls is increased in proportion as the diameter of one of the rolls is decreased.

For the purpose of agitating the kernels to facilitate the gravitating action thereof, as well as to assist the movement of the kernels through the several interstices between the rolls, shaker-arms 11, corresponding in number to the rolls, are rigidly secured at one end to the reduced ends 6 of said rolls and at their other ends to a transverse bar 12, provided with upper and lower spaced parallel cleats 12^a, between which journal-blocks 12^b for the reception of the reduced ends 13 of said shaker-arms 11 are adjustably mounted. An operating-handle 14 is centrally mounted upon bar 12, whereby rotating the handle will impart a like motion to the shaker-arms, and consequently rotate the rolls.

The end section 5 and the transverse bar 12 are provided with a series of horizontal slots 5^c and 12^c, one for each roll, and through which the respective reduced ends 6 of the rolls and the reduced ends 13 of the shaker-arms extend in order that the said reduced ends may have a limited transverse movement in said end section and transverse bar when the journal-blocks 5^b are moved to either side in changing the relative positions of the rolls. The journal-blocks may be retained in adjusted position by any suitable means, such as set-screws or thumb-nuts.

The invention involves the separation of the kernels into varying divisions, the kernels in each division possessing uniformity in size, and to this end a separate chute is provided and disposed beneath the several various-sized interstices existing between the aforementioned rolls which form passage-

ways, as previously set out. Each chute (severally indicated at 16, 17, and 18) embodies in its structure end members, to each successive pair of which the side sections 3 of 5 the machine-body contribute a common side member. End members 16^a, 17^a, and 18^a are inclined to a less degree as compared with end members 16^b, 17^b, and 18^b, the latter each having a portion of the material thereof 10 at the upper end disposed to lie at an angle to the major portion thereof, as at 16^c, 17^c, and 18^c, thus constituting a means of support therefor in conjunction with bars 15 and 15^a, which are disposed transverse of the body 15 and are secured by their ends to the side sections 3. The side sections 3 are provided adjacent the chutes with downward extensions coacting with the end members of the chutes and corresponding in contour to the boundary defined by said inclined end members of the chutes to form the latter. The said end members of the chutes are preferably formed of sheet metal. End members 16^a and 18^b are secured to the cleats 4^a and 5^a of the respective adjacent end sections 4 and 5. The 20 respective pair of adjacent end members 16^b and 17^a and 17^b and 18^a are secured to the adjacent transverse bar 15, which abuts both, the angular portions 16^c and 17^c of chutes 16 25 and 17, end members 16^b and 17^b thereof seating on the upper face of the said bars 15.

Should any kernels of the grain at the completion of travel throughout the length of the rolls be of such size as to be incapable of 30 passage through the interstices of varying sizes between the rolls, they will egress through enlarged openings 19, disposed in alinement with the interstices, said openings being for this express purpose of freeing the 35 machine of kernels of such size, the accommodation for which the machine lacks.

The grain is let into the machine at the highest point of the inclination of the rolls. For this purpose a hopper 20 is employed 40 suitably supported upon the machine-body from the end 5 and the sides 3. The said hopper directly overlies the rolls and carries a series of projecting plates 21, corresponding in number and arrangement to the rolls, 45 and preferably being of concave curvature at their lower corners 21^a, the function of which plates is to gage and regulate the feed and size of the kernels which are let into the separating mechanism. The plates are adjustably 50 retained upon the side of the hopper by means of slots 21^a, formed therein, and screws 21^b, engaging the hopper side.

As an additional aid in facilitating the separation of the kernels I prolong the chute end 55 members 17^a and 18^a upwardly, as at 22^a and 22^b, respectively, to permit the same to project in the path of the kernels in their gravitating movement along the inclined passage-ways formed by the interstices between the

rolls in order that any grain which possesses sufficient size to partially lodge between said rolls without passing through between the same may be caught by said extensions and prevented from entering other than their proper chute.

The operation may be briefly summed up as follows: The handle 14 and the common connecting-bar 12 are given rotary movement, thus causing the rolls to have a rotary movement and the grain having been placed into the hopper will gravitate throughout the length of the rolls until it arrives at its proper destination, at which point it will be let into its hopper. Thus kernels of small size are admitted to chute 18, kernels of medium size to chute 17, and kernels of large size to chute 16, kernels of extra large size being allowed to egress through openings 19. The action is simple, involving a gravitating movement supplemented by a rotating one to agitate the grain and the egress of the kernels of varying sizes when arriving at their proper chute.

Having thus fully described my invention, what I claim as new, and desire to secure by Letters Patent, is—

1. In a machine for separating seed-corn and the like, the combination with the frame or body, a series of rolls arranged in parallel and spaced relation and disposed at an incline within said frame or body, said rolls being adjustable and formed with decreasing gradations in diameters to form passage-ways therebetween, chutes disposed beneath said rolls and having portions thereof projecting upwardly into said passage-ways, and feed-hopper plates carried by said hopper and projecting inwardly toward aforesaid rolls, aforesaid frame or body having openings therein at its lowest end in alinement with the passage-ways formed by and between aforesaid rolls, and means for rotating said rolls, substantially as and for the purpose set forth.

2. A machine of the type set forth embodying a series of rolls arranged in parallel and spaced relation and disposed at an incline, said rolls being formed with successively-decreasing gradations in diameters, and a delivery-chute for each of the said gradations, said chutes having a portion thereof extended upwardly to project in the passage-ways formed between said rolls.

3. A machine of the type set forth, embodying a series of rolls arranged at an incline and spaced apart to form passage-ways therebetween, and chutes disposed beneath said rolls and having portions thereof projecting upwardly into said passage-ways.

4. A machine of the type set forth, embodying a series of inclined rolls arranged in spaced and parallel relation, and a machine-body in which said rolls are mounted, said body hav-

ing openings therein at its end in alinement with the passage-ways formed by and between said rolls.

5. In a machine of the type set forth, a body, a series of rolls mounted in spaced and parallel relation therein, said body having extensions on its side members, end members secured to said body and coacting with said extensions to form chutes, said forward

end of the members having angular portions, 10 and bars for securing said angular portions, said angular portions seating on said bars.

In testimony whereof I affix my signature in presence of two witnesses.

CHARLES LEE FRISBY.
